United States Patent Office.

NICHOLAS S. VEDDER, OF TROY, NEW YORK.

Letters Patent No. 94,675, dated September 7, 1869.

IMPROVEMENT IN COOKING-STOVES.

The Schedule referred to in these Letters Patent and making part of the same.

To all whom it may concern:

Be it known that I, NICHOLAS S. VEDDER, of Troy, in the county of Rensselaer, and State of New York, have invented new and useful Improvements in Water-Reservoir Cooking-Stoves or Ranges; and I do hereby declare the following to be a full, clear, and exact description thereof, reference being had to the accompanying drawings, and the letters of reference marked thereon, forming part of this specification, in which—

Figure 1 is a longitudinal vertical section, through the centre of my improved stove;

Figure 2 is a cross-vertical section, taken at the line $x x$, fig. 1;

Figure 3, a rear view of my improved stove, with the water-reservoir removed; and

Figure 4 is a perspective view of the reservoir.

Similar letters of reference denote like parts in the different figures.

My invention consists, first, in providing a heating-chamber or chambers, against the front side of that portion of the water-reservoir which extends above the top plate of the stove, in combination with a heating-chamber or chambers against and between the front part of the reservoir, which is below the top plate of the stove, and the back plate of the stove; and

My invention consists, secondly, in the heating-chamber or chambers against the front side of the upper part of the reservoir, and in communication with the descending oven-heating flue or flues, in combination with a heating-chamber or chambers along the front side of the lower portion of reservoir, and in communication with the rear ascending or exit flue of the stove; and

My invention consists, thirdly, in combination with the above, the dampers, for regulating the passage of hot-gases of combustion, through the upper and lower heating-chambers, along or against the front side of the reservoir.

To enable others skilled in the art to make and use my improved stove, I will now proceed to describe fully its construction and operation, to wit:

In the accompanying drawings—

A represents a cooking-stove, of the usual form of construction, and in addition thereto, the flues B B, rising over the top plate of the stove, and the hot-air space or passage C.

At the rear and outside of the stove, D is the draught-flue, and

E E are the ascending and descending oven-heating flues.

F is a damper, arranged to regulate the draught, and also to divert the heat passing over the top of the oven, and force it into the ascending or descending flues E E.

G is a slide, covering a hole in the back plate of

the stove, and leading into the hot-air flues or passages between the lower part of the reservoir and the back part of the stove.

H is the water-reservoir, with an extension, I, equal to nearly one-half of the depth of the reservoir.

This extension is made of such form as to cover or overlap the flues B B, and avoid the draught-flue D, and fitting close down on to the top plate of the stove.

The lower portion of the reservoir comes in contact with the ends $a a$ and bottom b , of the air-passage C, and fitting closely, makes an air-tight passage, C, between the lower portion of the reservoir and the back part of the stove, which is constructed with the draught-flue D, by the damper G, and is connected with the ascending and descending flues E E, through the space between the edge of the top plate of the stove and the front of the reservoir.

The reservoir is also provided with lids, applied as deemed most expedient, and with a vent, K.

l l are legs or projections, to assist in the support of the reservoir, and keeping it away from the back plate of the stove.

One or both of the division plates between the flues are returned at right angles above the top of the oven, forming a flange for the damper F to close against.

The operation of my improved stove is as follows:

With the damper F open, and the slide G closed, the major part of the heat passing over the top of the oven, is drawn into the central or exit flue D, and passes up the pipe, a portion circulating through the ascending and descending flues E E, up the flues B B, and from thence into the space C, producing a moderate heat against the whole extent of the front side of the water-reservoir, and when it is desired to increase the heat against the reservoir, the damper F is closed, and the heat, which is thus shut off from the exit flue is forced into the ascending and descending flues, rising up above the top plate of the stove, and heating the upper part of the reservoir, and then drawn down between the edge of the top plate of the stove and the front of the reservoir into the chamber C, from whence it passes into the exit flue D, the slide G, of course, being open, so that, it will be seen, the reservoir contents may be kept at any degree of temperature.

Having thus described the construction and operation of my improved stove,

What I claim as new, and desire to secure by Letters Patent, is—

1. The heating-chamber or chambers against the front side of the reservoir, above the top plate of the stove, in combination with a heating-chamber or chambers, between the front side of the reservoir, below the top plate of the stove and the back plate of

the stove, substantially as and for the purpose hereinbefore set forth.

2. The heating-chamber or chambers against the front side of the upper portion of the reservoir, in communication with the descending oven-heating flue or flues, in combination with the chamber or chambers along the front side of the lower portion of the reservoir, and in communication with rear ascending or exit flue.

3. In combination with the above, the dampers, arranged and operating as and for the purpose hereinbefore set forth.

In testimony whereof, I have hereunto set my hand, this 7th of June, A. D. 1869.

NICHOLAS S. VEDDER.
